BRUSH HOLDER AND SCRAPER ATTACHMENT FOR PAINT CANS

Joseph L. Kosorok, Red Lodge, Mont.

Application July 7, 1950, Serial No. 172,499

5 Claims. (Cl. 220—90)

1

My invention relates to paint brush holders and has for its primary object the provision of a device for this purpose which may be readily attached to and removed from a conventional paint can.

A still further object of my invention is the provision of a device which may be utilized in conjunction with paint cans which vary, within limits, in diameter and size.

Another object of my invention is the provision of a device of the class described which is provided with a wiping plate, the wiping surfaces of which are spaced radially inwardly from the sides of the peripheral edge portion of the opening of the paint can, whereby all of the paint removed from the brush by wiping engagement will drip directly back into the pail.

Another important object of my invention is the provision of a brush holder, the paint brush-engaging jaws of which may be readily moved from a position overlying the opening in the paint can to an inoperative position remote therefrom.

A still further object of my invention is the provision of a device which may be inexpensively produced, which is rugged in construction and durable in use, and which will occupy but a minimum of space when packed for storage or shipment.

The above and still further objects of my invention will become apparent from the following detailed specification, appended claims, and attached drawings.

Referring to the drawings, wherein like characters indicate like parts throughout the several views:

Fig. 1 is a view in side elevation of my novel device secured to a paint can;

Fig. 2 is a top plan view of the structure of Fig. 1, on an enlarged scale;

Fig. 3 is a fragmentary view in end elevation, as seen from the right of Fig. 1 and on a reduced scale; and

Fig. 4 is a view in section taken on the line 4—4 of Fig. 2.

Referring with greater particularity to the drawings, a paint can A of conventional manufacture and size is provided with a cover-receiving opening B at its upper end and a marginal flange C, which projects radially inwardly from the circular side wall D.

According to my invention, I provide a pair of preferably segmental clamping members 1 and 2 which are adapted to be frictionally retained against the side wall D of the paint can A in opposed relationship by means of coil tension

2

springs 3 which have their opposite ends securely anchored in openings 4 in adjacent side edges of the clamping members 1 and 2.

Preferably and as shown, the clamping members 1 and 2 are retained in position, whereby their upper end portions 5 project upwardly from the flange C at the upper end of the can A. Preferably and as shown, the opposite upper edge portions of the clamping members 1 and 2 are provided with upstanding ears 6. Coiled tension springs 7 have one end securely anchored in the ears 6, as indicated at 8, and their opposite ends secured one each in apertures 9 in the corner positions 10 of a wiper plate 11. As shown, the corner portions 10 are adapted to overlie the flange C at the upper end of the can A, preferably in spaced relation thereto, as shown particularly by Figs. 1-3 inclusive. Plate 11 is provided with a central opening 12, which is preferably rectangular in form so as to provide a plurality of straight wiper surfaces 13 which are spaced radially inwardly from the flange C for a purpose which will hereinafter become apparent.

An arm 14 has one end pivotally secured on a horizontal axis to the intermediate portion of clamping member 1, as indicated at 15, for limited movements to and from the full and dotted line positions of Fig. 1. At its free end, arm 14 is provided with a brush-holding member 16 which comprises a pair of jaw-forming members 17 and 18, each of which is notched adjacent its free outer end to provide a mouth 19. A coil tension spring 20 biases the jaws toward a position to frictionally grip the handle E of a paint brush F, whereas the handles 21 on each of the jaws 17 and 18 facilitates manual spreading of the jaws to release the handle E of the brush F therefrom.

It will be noted that, when the arm 14 is moved to the operative position indicated by the dotted lines of Fig. 1, the brush F will be held in a vertical position over the openings 12 and B, whereby paint dripping from the bristles G will drop back into the can without waste. Furthermore, when it is deemed advisable to remove excess paint from the bristles G by wiping contact, this may be accomplished by causing same to engage the straight wiping surfaces 13 of the wiper plate 11. Here again, in view of the fact that the wiping surfaces 13 are radially inwardly-disposed with respect to the flange C, all paint removed from the brush will drop back into the can A without waste.

My invention has been thoroughly tested and found to be completely satisfactory for the ac-

compliment of the above objects; and, while I have illustrated and described a preferred embodiment of my invention, I wish it to be understood that the same is capable of modification without departure from the spirit and scope of the invention as set forth in the appended claims.

What I claim is:

1. In a device of the class described, a wiper plate having a central opening therein and circumferentially-spaced peripheral portions which are adapted to overlie the upper marginal edge of an open top container, a pair of clamping members adapted to engage the side wall of said container in opposed relation, yielding means connecting adjacent side edge portions of said clamping members whereby to cause frictional anchoring engagement between the said members and the wall of said container, yielding means connecting the upper portions of said anchoring members to said plate at circumferentially-spaced points about said container, an arm pivotally secured to one of said clamping members for limited swinging movements about a horizontal axis from an inoperative position adjacent the lower end of said container to an operative position wherein said arm projects above the level of said plate, and a brush-holding member carried by the free end of said arm and adapted to overlie the opening in said plate when said arm is swung to its operative position.

2. The structure defined in claim 1 in which the central opening in said plate is provided with a straight brush-wiping edge.

3. In a device of the class described, a rectangular wiper plate having a central opening therein, the corners of said wiper plate adapted to overlie the marginal edge of an open-topped paint can, a pair of segmental clamping members, coil springs connecting the opposite upper end portions of each of said clamping members to adjacent corners of said wiper plate and positioning said clamping members in diametrically-opposed relationship on said container, coil tension springs connecting the adjacent side edges of said clamping members in a plane below the level of said wiper plate, an arm pivotally secured to one of said clamping members for limited swinging movements about a horizontal axis from an inoperative position adjacent the lower end of the container to an operative position wherein the arm projects above the level of said wiper plate, and a brush-holding member carried by the free end of said arm and adapted to overlie the opening in said wiper plate when said arm is swung to its operative position.

4. The structure defined in claim 3 in which said central opening is provided with a plurality of straight wiper surfaces.

5. The structure defined in claim 3 in which said brush-holding member comprises a pair of clamping jaws and in further combination with yielding means biasing said jaws toward brush handle-engaging position.

JOSEPH L. KOSOROK.
